US0D1066158S

(12) **United States Design Patent** (10) **Patent No.:** **US D1,066,158 S**
(45) **Date of Patent:** **** Mar. 11, 2025**

(54) **VEHICLE REAR BUMPER VALANCE PANEL**

(71) Applicant: **GM GLOBAL TECHNOLOGY OPERATIONS LLC**, Detroit, MI (US)

(72) Inventor: **Tyler L. H. Moffett**, Royal Oak, MI (US)

(73) Assignee: **GM GLOBAL TECHNOLOGY OPERATIONS LLC**, Detroit, MI (US)

(**) Term: **15 Years**

(21) Appl. No.: **29/883,552**

(22) Filed: **Jan. 31, 2023**

(51) LOC (15) Cl. **12-16**

(52) U.S. Cl.

USPC **D12/169**

CLAIM

The ornamental design for a vehicle rear bumper valance panel, as shown and described.

DESCRIPTION

FIG. 1 is a front and left side perspective view of a vehicle rear bumper valance panel showing my new design;

FIG. 2 is a front elevation view of the vehicle rear bumper valance panel of FIG. 1;

FIG. 3 is a left side elevation view thereof;

FIG. 4 is a right side elevation view thereof;

FIG. 5 is a back elevation view thereof;

FIG. 6 is a top plan view thereof; and,

FIG. 7 is a bottom plan view thereof.

The broken lines in the drawings depict portions of the vehicle rear bumper valance panel that form no part of the claimed design.
